UNITED STATES PATENT OFFICE.

ROBERT W. SOPER, OF DETROIT, MICHIGAN, ASSIGNOR OF ONE-HALF TO
MARY HAYES, OF SAME PLACE.

CASH-CARRIER APPARATUS.

SPECIFICATION forming part of Letters Patent No. 416,870, dated December 10, 1889.

Application filed June 24, 1889. Serial No. 315,329. (No model.)

To all whom it may concern:

Be it known that I, ROBERT W. SOPER, a citizen of the United States, residing at Detroit, in the county of Wayne and State of Michigan, have invented certain new and useful Improvements in Cash-Carrier Apparatus; and I declare the following to be a full, clear, and exact description of the invention, such as will enable others skilled in the art to which it pertains to make and use the same, reference being had to the accompanying drawings, which form a part of this specification.

In the drawings, Figure 1 is a side elevation. Fig. 2 is an end elevation. Fig. 3 is a plan view. Fig. 4 is a side elevation, partly in section. Fig. 5 is a section on the line xx , Fig. 4. Fig. 6 is a plan of the movable stop; and Fig. 7 is a side elevation, partly in section, of a modification of the projecting device.

It is the purpose of my invention to produce a cash or parcel carrier apparatus in which the car is propelled by a chain, which is housed in an upright slotted tube actuated by a depending strap and returned to its initial position by a spring at the top of the tube, the construction being such that the lower end of the chain is deflected into a horizontal direction, so that as the chain is forced downward by the strap it will be projected horizontally against the car, and so impart a thrust to it which will cause it to traverse the line to its distant end; also, in connection with the foregoing, I place a roller in the angle where said chain flexes adapted to relieve the friction and so assist the spring to return the chain to its initial position, and I also place a wearing-plate opposite said roller.

In carrying out my invention, A represents the track. B are the depending parts by which it is supported.

C is a brace rod or wire.

D is the car which carries the cash or parcel holder E.

F is the upright, and F' the horizontal portion, of the tube which contains the propelling-chain. The horizontal portion is open along its upper side at f'' , and the upright portion 50 is open along its back at f .

F² is an angle-fitting, into which the ends

of the sections F F' of the pipe are seated. This fitting is preferably provided on the lower side of its interior with a steel wearing plate or bearing f^2 , to receive and sustain the 55 wear of the chain when it is being forced down by the strap, and in its upper side, in the angle between the two pipes, is an anti-friction roller f^3 , designed to relieve the spring of the friction that would otherwise 60 ensue by the dragging of the chain at this point as it is being returned to its initial position.

G is the propelling-chain, constituting a flexible shaft composed of links g , preferably 65 curved, as shown, so as more easily to flex around the roller f^3 . At its lower end an ear or push-piece G' projects up through the slot f' to engage and push the car.

H is the actuating-strap, and H' a handle. 70 An engaging device H² engages the strap with the chain or its guide G³, and travels up and down in the open slot f .

I is a stop, preferably adjustable, for arresting the downward pull of the chain; and J 75 is a spring for retracting or returning the chain to its initial position.

K represents a set of spring-jaws, which engage with the end of the car, which is preferably recessed at d , to enable the jaws to 80 hold with a strong frictional bearing. The purpose is twofold—they serve to cushion and grip the car when it arrives, and also to hold it until the operator has exerted a considerable pull on the strap or cord before it 85 is let loose. This insures that as the jaws do let loose, the gathered energy, when thus released, will result in an impulse sufficient to impel the car to its distant station. For a short track these spring-jaws may be given a 90 lighter tension, and for a long line they may be given a strong tension. The car may also have the usual cushion d' at its end, and this may come to a bearing against the ear or push-piece G' at the end of the chain. The 95 provision of the wearing-plate f^2 and roller or pulley f^3 reduces the wear to a minimum, and renders the return of the chain very easy. They also co-operate to make the whole device operate smoothly and quietly.

To take out the chain it is only necessary to remove the plug or cap f^5 , detach the chain

from its fastening to the strap, and it may be drawn out at f^5 . By removing the plug J' the spring J may be removed. The chain-tube is engaged with the post by clamps b , which also serve to strengthen and stiffen the tube, and a cushion of rubber or equivalent G^2 is preferably located back of the ear or push-piece G' , to relieve the jar as the car comes in against the chain. A similar cushion g' is located to relieve the jar as the spring draws the chain back to its initial position. I prefer also to locate a rubber or other cushion at i to sustain the jar as the strap is drawn down.

15 The track-wire A is preferably, as shown in Fig. 3 at a , carried diagonally through the fitting F^2 , so as to avoid the chain, and, extending thence back, constitutes a brace, as shown at a' .

20 d^2 represents a fork which projects up from the car and embraces the track-wire, thus effectually preventing the car from leaving the wire.

25 The chain may be made of fiber instead of metal, thus making a lighter structure and largely reducing the friction and wear in the angle-fitting.

30 I would have it understood that much of my invention is not limited to a device with a chain-pusher, but is equally applicable where any flexible shaft or pusher is employed, and especially where said pusher substantially fills the tube. So, also, it is not absolutely essential that the tube should be slotted, for 35 the propelling force may be exerted directly into the upper tube by a plunger L directly connected with the chain G , and operated by the actuating-cord H , and the blow may be imparted to a shaft L' projecting out of the 40 lower end of the tube F^2 , as shown in Fig. 7.

What I claim is—

1. In a cash or parcel carrier apparatus, the combination of the line-wire and the car adapted to travel thereon, a tube having upright and horizontal sections, a flexible car-propelling shaft or pusher located therein and substantially filling the tube, means connected with the upper end of said shaft adapted to force the same downward, means connected with its lower end adapted to deliver the thrust of the shaft to the car, and means for returning the shaft to its initial position, substantially as described.

2. In a cash or parcel carrier apparatus, 55 the combination of the line-wire and the car

adapted to travel thereon, a tube having upright and horizontal sections, a car-propelling-chain pusher located therein, means connected with the upper end of the chain adapted to force the same downward, means connected with its lower end adapted to deliver the thrust of the chain to the car, and means for returning the chain to its initial position, substantially as described.

3. In a cash or parcel carrier apparatus, 60 the combination of the line-wire and car adapted to travel thereon, a tube having a vertical and a horizontal section, a flexible shaft or pusher located in said tube and adapted at its lower end to impart a thrust to 70 the car, said pusher engaged at its upper end with an actuating cord or strap located wholly outside of said tube, substantially as described.

4. In a cash or parcel carrier, the combination, with the line-wire, the car, and a tube having an upright and a horizontal section, of a flexible pusher located in said tube and substantially filling the same, an anti-friction roller in the angle formed by said sections, 80 means for forcing said pusher downward and outward against the car, and means for returning the pusher to its initial position, substantially as described.

5. The combination, in a cash-carrier apparatus, of a slotted tube having an upright section and a horizontal section, a flexible car-propelling-chain pusher located in said tube and substantially filling the same, and an actuating strap or cord engaged with the chain 90 or its support at or near its upper end, substantially as described.

6. The combination, with the slotted tube having an upright and a horizontal section, chain-pusher, actuating-strap, and retracting-spring, of the anti-friction roller located in the angle between the two sections of pipe, substantially as and for the purposes described.

7. The combination, with the slotted tube $F F'$, of the angle-fitting F^2 , provided with a 100 wearing-plate and anti-friction roller, and in connection therewith a flexible propelling-shaft located in said tube, and means for actuating said shaft, substantially as described.

In testimony whereof I sign this specification in the presence of two witnesses.

ROBERT W. SOPER.
